UNITED STATES PATENT OFFICE.

CHARLES A. DIGGINS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

COLOR INDICATOR FOR WEFT-REPLENISHING LOOMS.

Application filed November 18, 1924. Serial No. 750,670.

This invention relates to improvements in weft replenishing mechanism for looms of the multi-color type and more particularly to the mechanism for keeping the replenishing mechanism in register with the active shuttle.

In looms of this type there are usually provided several shuttles which are brought into action one at a time and the replenishing mechanism is arranged to supply a bobbin of the proper color for any shuttle. In relatively slow moving looms the color indicating mechanism is controlled by a direct connection to the box lifter rod, inasmuch as sufficient time elapses between the arrival of the boxes to picking position and the subsequent arrival of the active shuttle under the magazine to permit a bobbin to move from any of the bobbin stacks to the common transfer position. In faster running looms, however, this interval of time is insufficient and it is necessary to provide intermediate mechanism by which the color indication can be given to the replenishing mechanism before the boxes have been moved completely to picking position, thereby affording more time for the bobbin to fall to transfer position.

One method of providing the color indication in advance of the complete motion of the boxes is shown in Patent No. 1,030,748. The mechanism shown in said patent is not readily adaptable to the type of box motion shown herein nor is it capable of certain adjustments found desirable when the motion disclosed herein is employed.

One object of my present invention is to provide a color indication for weft replenishing looms wherein the compound levers are adjustable both vertically and horizontally with respect to the cam faces by which they are actuated.

It is a further object of my invention to separate the cams from the box lever lifting mechanism so that said cams may have adjustments independent of the box lifting mechanism.

A still further object of my invention is to provide cams of similar construction, the centers of which are all located on the same side of the compound levers, each cam being independently adjustable with respect

to its particular actuator and all of the cams being movable about a common center.

With these and other objects in view which will appear as the description proceeds, my invention resides in the combination and arrangement of parts hereinafter described and set forth in the claims.

I the accompanying drawings, wherein I have shown one form of my invention,

Fig. 1 is a side elevation of a loom having my invention applied thereto.

Fig. 2 is a rear elevation of a portion of the mechanism shown in Fig. 1,

Fig. 3 is a horizontal section looking downwardly along line 3—3 of Fig. 1,

Fig. 4 is a top plan view of the compound levers by means of which the color indication is given to the replenishing mechanism, and

Fig. 5 is a diagrammatic view showing the means of conveying the indication to the color slide of the usual multi-color weft replenishing mechanism.

Referring more particularly to the drawings it will be seen that I have provided a loom frame 10 to which is secured a plate 11 having pivotally mounted on the rear part 80 thereof vibrator levers 12 on which are rotatably mounted vibrator gears 13. Said gears 13 are raised and lowered by means of pattern mechanism (not shown) to be operatively connected with one or the other of the cylinders 14 and said gears are each provided with connectors 15. Extending laterally from the plate 11 is a stud 16 on which is mounted a pair of bell crank levers 17 and 18, respectively. I have shown herein 90 mechanism appropriate for a four color loom but it is to be understood that the number of levers mounted on stud 16 may be varied according to the number of shuttles employed by the loom. Extending upwardly from each of the levers 17 and 18 is a link 19 having pivotal connection with the forward end of connector 15. The bell crank levers 17 and 18 have forwardly and rearwardly extending arms 20 and 21, respectively, from which depend links 22 and 23, respectively.

The links are pivotally connected at their lower extremities with the box lifter lever 24 the forward end of which is connected with the boxes through connector 25 and the rear portion of which is

provided with a fixed stud 26. The mechanism thus far described is old and of the usual construction and for further description as to the construction and operation of the same reference may be had to patent to Knowles, No. 221,237.

My invention relates more particularly to the mechanism for controlling the color indication of the replenishing features of the 10 loom and in carrying out my invention I provide a stand 30 secured to the loom side by means of bolts 31 which pass through slots 32 thus affording horizontal adjustment for the said stand 30. The upper portion 33 of the stand 30 is provided with a stud 34 upon which are pivotally mounted a pair of cam levers 35 and 36, respectively, each lever being pivotally connected as at 37 to a compound link formed of lower and 20 upper members 38 and 39, respectively. The upper portions of the members 39 are pivotally connected to the arms 20 and 21 so as to require movement of the cam levers whenever the bell crank levers 17 and 18 25 move. A bolt and slot adjustment between the links 38 and 39, indicated generally at 40 affords adjustment between the bell crank levers and the cam levers. Each of said cam levers is provided with dwell portions 41 and 42 struck from different radii around stud 34 and connected by a lifting surface or cam 43. The dwell portions extend on each side of the lifting surfaces 43.

Stand 30 is provided with parallel vertical guides 44 between which is slidably mounted a foot 45 having a slot 46 which receives a bolt 47 extending from the stand 30. In this way the foot 45 may be adjusted vertically with respect to the stand 40. The lower portion of said foot is provided with another slot 48 which receives stud 26 to prevent end motion of the lever 24, thereby keeping said lever in substantially the same vertical position for all 45 positions of the bell crank levers and for all adjusted positions of the foot 45.

Extending laterally from the foot 45 is an offset 49 provided with a pair of parallel ways 50 between which is received the 50 lower end of an arm 51. A slot 52 formed in the offset 49 permits horizontal adjustment of the arm 51 with respect to the foot 45.

The compound lever for controlling the 55 weft replenishing mechanism is shown more particularly in Fig. 4 where it will be seen that I have provided a relatively short lever 54 pivoted centrally thereof on arm 51 and having the rear end thereof provided 60 with a roll 55 and the forward end with a stud 56. A second lever 57 of substantially twice the length as the lever 54 is pivoted at the central portion thereof on stud 56, has the rear end thereof provided with a roll 65 58, and has the forward end thereof attached

to an upwardly extending connector 59. Shaft 61 is suitably journaled in fixed bearings and extends across the loom, that portion of said shaft adjacent the box motion being provided with a slotted lever 60 to have adjustable connection with connector 59 and that end of the shaft 61 adjacent the replenishing mechanism being provided with a lever 62 which is operatively connected by means of link 63 to lever 64 pivoted as at 65 to a fixed part of the replenishing mechanism. The upper end of the lever 64 has operative connection with a horizontal shaft 66 mounted for angular and sliding motion with respect to the replenishing mechanism. Said shaft has secured thereto fingers, one of which is indicated at 67 to cooperate with vertical slides 68. The replenishing mechanism forms no part of my present invention and for a further description of the construction and operation of the same reference may be had to Patent No. 1,030,748. It is sufficient for an understanding of my present invention to indicate that when the lever 60 is given any one of its four angular positions the operating fingers on the shaft 66 will be placed in vertical alignment with that slide which will correspond with the active shuttle.

As shown in the drawings the bell crank levers are so placed as to position the second box opposite the lay. Roll 58 is in raised position while roll 55 is depressed which gives lever 60 a corresponding position. When the bell crank levers change their position to bring any of the other boxes opposite the race, there is a corresponding change in the position of lever 60 due to the cams so that the color indication always registers with the active shuttle. It is to be understood that the rolls 55 and 58, when changing their vertical position, assume their final position before the crank levers stop moving so that the proper bobbin can be released from its stack and started toward transfer position prior to the picking. This is brought about by placing the rolls and the cam surfaces 43 so that the rolls will lie on opposite sides of the surface 43 and equally spaced therefrom when the cam lever is in its two extreme positions.

From the foregoing it will be seen that by reason of the adjustability of the various parts the position of the rolls can be set in any desired position. The movement of the arm 51 horizontally affords such an adjustment and the vertical movement of foot 45 will vary the position of lever 60 so that the vertical distances through which the link 63 passes will be substantially equal. Also, stud 34 can be moved independently of stud 16 in a horizontal direction and the relation of the cams with respect to the bell cranks can be adjusted in a vertical direction, by means of the bolt and slot connection indicated at

40. It will further be noted that when arm 51 is moved, both of the rolls are moved with respect to the cams in the same direction, a condition not thought to prevail hereinbefore in the art. It will also be noted that the cams are adjustable independently of the box lifting levers and are movable bodily with respect thereto. Part of the adjustments described are possible because the 10 rolls 55 and 58 are substantially in alignment and the cams of the cam levers face in the same direction.

Having thus described my invention it will be apparent that changes and modifications may be made therein by those skilled in the art without departing from the spirit and scope of the invention, and I do not wish to be limited to the details herein disclosed, but what I claim is:

20. 1. In a color indicator for weft replenishing looms having a plurality of shuttle boxes, a pair of box lifting angle levers having arms extending in opposite directions, a pivotal support common to said angle levers located between the oppositely extending arms, a cam lever for each angle lever, each cam lever having relatively high and low cam surfaces, a system of compound levers to cooperate with the high and low surfaces of 30 the cam levers, the high and low surfaces of the cam levers being concentric, and connections between the oppositely extending ends of the angle levers and the cam levers to cause said cam levers to move with the angle levers.

2. In a color indicator for weft replenishing looms having a plurality of boxes, a pair of box lifting angle levers having oppositely extending arms, a common pivotal support for said angle levers, a pair of cam levers, one for each angle lever, each cam lever having a cam surface with high and low areas, the cam surfaces facing in the same direction, and a system of compound 40 color indicating levers operatively associated with the surfaces, said levers being movable toward and from the surfaces, the surfaces being movable with the angle levers independently of each other and the compound levers.

3. In a color indicator for weft replenishing looms having a plurality of shuttle boxes, a pair of oppositely disposed box lifting angle levers, a common pivotal support for 50 said angle levers, a pair of cam levers each having a cam surface, a common pivotal support for said cam levers spaced from and movable with respect to the support for the

angle levers, operative connections between the angle and cam levers to cause one of the 60 cam levers to move whenever the corresponding angle lever moves, and a system of compound color indicating levers operatively associated with the cam levers.

4. In a color indicator for a weft replenishing loom having a plurality of boxes, a pair of oppositely disposed box lifting angle levers for the shuttle boxes, a common pivotal support for said angle levers, a pair of cam levers, one for each angle lever, a common support for said cam levers movable bodily with respect to the support for the angle levers, the cam surfaces facing in the same direction, a system of compound color indicating levers operatively associated 70 with the cam levers, and a support for said compound levers movable toward and from the common support for the cam levers.

5. In a color indicator for weft replenishing looms having a plurality of boxes, a system of compound levers operatively connected to the indicator and having a pair of closely adjacent ends to be operated upon, a pair of cam levers one for each of said ends of the compound lever, box lifting angle levers operatively connected to the cam levers, and supports for the system of compound levers, cam levers and angle levers, all of 80 said supports being movable relatively to each other.

6. In a color indicator for weft replenishing looms having a plurality of boxes, a system of compound levers having an end operatively connected to the indicator and having a pair of closely adjacent ends to be operated upon, a pair of cam levers one for each of the ends to be operated on, a cam support for said cam levers, a pair of box lifting angle levers operatively connected to the cam levers, and a common support for 90 said box lifting angle levers.

7. In a color indicator for weft replenishing looms having a plurality of boxes, a system of compound levers having connection with the indicator and a pair of ends to be 100 acted upon, a cam lever to act on each of the ends, a box lifting lever for each cam lever, both of said cam levers being movable in one direction to correspond to the lower position of said ends and movable in the opposite direction to correspond to the raised position of said ends.

In testimony whereof I have hereunto affixed my signature.

CHARLES A. DIGGINS.
